UNITED STATES PATENT OFFICE.

EDWARD S. PRESTON, OF CHICAGO, ILLINOIS.

SWITCHING-SOCKET.

1,323,200.

Specification of Letters Patent. Patented Nov. 25, 1919.

Application filed January 6, 1917. Serial No. 140,900.

To all whom it may concern:

Be it known that I, EDWARD S. PRESTON, citizen of the United States, residing at Chicago, in the county of Cook and State of Illinois, have invented certain new and useful Improvements in Switching-Sockets; and I do hereby declare the following to be a full, clear, and exact description of the invention, such as will enable others skilled 10 in the art to which it appertains to make and use the same.

My invention relates to electrical fittings and more particularly to switching sockets or connectors as used for controlling low 15 voltage circuits, its general objects being to provide an unusually simple, cheap and effective construction for appliances of this class. While applicable to widely varying types, my invention is particularly adapted 20 for use in equipping sockets for automobile lamps and is therefore disclosed in such embodiments in the accompanying drawings and in the following specification, from both of which the further objects of my invention 25 will be apparent.

In the drawings,

Figure 1 is a central longitudinal section through a lamp-socket embodying my invention as applied to a socalled gage lamp.

30 Fig. 2 is a fragmentary perspective view of the casing of Fig. 1.

Fig. 3 is a similar section showing my invention as embodied in a socket having a detachable and partly rotatable plug.

35 Fig. 4 is a fragmentary elevation of a portion of Fig. 3.

Fig. 5 is a transverse section through Fig. 3 along the line 5—5.

40 Fig. 6 is a perspective view of the upper insulating body of the socket of Fig. 1.

In accomplishing the purposes of my invention, I employ a current-conducting element disposed at one side of the axis of the socket casing, this element being preferably 45 of the well known spring-pressed plunger type common in sockets and connectors of this general class. Associated with this contact element and operatively opposed to it, I employ a second contact element, prefer- 50 ably in the shape of a plate extending trans- versely of the socket casing and so embedded in a groove in the end of an insulating body that the walls of the said groove will prevent a lateral or rotational movement of this 55 second contact element with respect to said insulating body. The first named conduct-

ing element and the insulating body which acts as a carrier for the transverse plate are mounted for relative rotation about the axis of the socket, this being accomplished in 60 various ways according to the particular manner in which the appliance is to be used. For example, Fig. 1 shows a flanged socket comprising a casing 1 having an insulating cylinder 2 fast therein and having bayonet 65 slots 3 at its upper end for interlocking with pins 4 on the shell 5 of a lamp-holder, which holder in turn is equipped for interlocking with the metal shell 6 on the base of a lamp 7. Fast within the holder shell 5 is an 70 insulating member 8 carrying a spring plunger 9 extending axially of the shell 5 into contact with the exposed axial contact on the base of the lamp. The plunger 9 is electrically connected through the spring 10 75 with the cylinder 11 which houses the head of the plunger, and the lower end of this cylinder is suitably secured (as by riveting a contracted tip 12) to a metal contact plate 13 extending transversely of the shell 5 but 80 terminating short of the latter. This plate 13 is set into a groove formed in the lower end of the insulator 8, so that the walls of the groove will engage the sides to the plate to prevent the latter from rotating 85 about the tip 12. Secured to the insulator 8 and projecting through a slot in the shell 5 which extends for (say) a quarter of the circumference around this shell, is a handle 14, by means of which the insulator 8 and the 90 plate carried thereby may be partially rotated about the axis of the said shell, thereby bringing a plunger 24 carried by a wire terminal 25 (carried by the insulator 2 now axially of the casing 1) out of contact with 95 the plate 13 and hence rupturing the circuit. (The other terminal of the circuit in this case is formed through the casing 1 and the grounded shell 5 from a ground 15 to the metal shell 6 of the lamp). 100

In Fig. 2, the socket illustrated has a casing 16 equipped at opposite ends with bayonet slots for interlocking respectively with a lamp 7 and a wire-terminal plug, and this casing has fast within it an insulating body 17 carrying two electrically interconnected spring-pressed plungers 18 and 19, the former of which extends axially of the casing 16 and into contact with the axial lamp terminal on the lamp base. The other plunger 19 extends parallel to, but to one side of the axis of the casing and is shown in 110

Fig. 3 as contacting with a transverse plate 13 mortised into the end of the body 2^A of the said plug. Secured to the plate 13 to prevent movement of the latter longitudinally of the plug, is a wire terminal 21, while a companion terminal 22 is grounded to the metal shell 23 of the plug and hence through the casing 16 to the lateral terminal of the lamp. In this case, the bayonet slots at the lower end of the casing are laterally extending so as to permit the rotating of the plug with respect to the axis of the casing for about a quarter-turn, thereby allowing the plug to be locked either in the position of Figs. 3 and 4, or in a position in which the plate 13 extends transversely of its position in the aforesaid case. This movement carries the plate 13 to the position shown in dotted lines in Fig. 5, thereby bringing the downwardly extending plunger 19 into contact with the insulating body 2^A of the plug and hence rupturing the circuit.

From the above, it will be obvious that in either case I am employing a cheap and simple construction, and since I use walls of the groove in the insulating carrier for the transverse plate as means for preventing rotation of this plate, I do not require a rigid fastening of this plate to the metal conducting element which extends longitudinally of the casing. Moreover, it will be obvious from the drawings that a half-turn of the lamp-holder with respect to the socket casing of Fig. 1, or a half-turn of the plug of Fig. 2 with respect to the casing 16, will in no way alter the effective operation of these appliances. Consequently, they may

be employed by the unskilled without requiring instructions or particular accuracy of any kind. It will also be obvious that in each case the spring plungers not only insure good electrical connections but also hold the rotatable members firmly interlocked with the casings or shells carrying the same. However, while I have shown and described my invention in embodiments including elements corresponding in size and shape to those now commonly used in sockets or connectors of this general class, I do not wish to be limited to the details of the construction and arrangement herein disclosed, it being obvious that both might be varied considerably without departing from the spirit of my invention.

I claim as my invention:

In an electrical connector, a tubular casing, a lamp in one end of the casing having the same relative position thereto in both the on and off status, an insulating body fixed in the other end of the casing, a yielding contact carried by said body at one side of the axis of the casing and having means for connection with a wire terminal, an intermediate insulating body rotatably mounted within the casing, and a contact carried by the intermediate body having one end yielding and coincident with the axis of the casing and constantly in contact with the lamp and its other end fixedly mounted and disposed transverse the casing for coöperation with the other yielding contact whereby rotation of the intermediate body will move said contacts into and out of engagement.

EDWARD S. PRESTON
